UNITED STATES PATENT OFFICE.

FRANK A. BALDWIN, OF GRAND RAPIDS, MICHIGAN.

DESIGN FOR A CIGAR-SHIELD.

SPECIFICATION forming part of Design No. 29,785, dated December 13, 1898.

Application filed October 24, 1898. Serial No. 694,486. Term of patent 7 years.

To all whom it may concern:

- Be it known that I, FRANK A. BALDWIN, a citizen of the United States, residing at Grand Rapids, in the county of Kent and State of Michigan, have invented and produced a new and original Design for Cigar-Shields, of which the following is a specification, reference being had to the accompanying drawings, forming a part thereof.
- Figure 1 is a perspective of a cigar-shield embodying my design, and Fig. 2 a plan view of the same.
- Like letters refer to like parts in both of the figures.
- As shown in the drawings, the leading or material features of my design are a vertically-corrugated plate having rounded corners and a downwardly-open clip on the upper part of one of the corrugations. The plate
- A is longitudinally corrugated, each corrugation being concave on its inner side C and

convex on its outer side B, forming longitudinal ribs C' between the concave portions C on the inner side and deep grooves B' on the outer side between the convex portions B. 25 The respective corners of said plate are also rounded, as shown, and on the upper part of the convex side of the middle corrugation is a depending downwardly-open spring-clip, convex at its upper part and turned slightly inward at its lower end. 30

Having thus fully described my invention, what I claim as new, and desire to secure by Letters Patent, is—

The design for a cigar-shield substantially 35 as herein shown and described.

In testimony whereof I affix my signature in presence of two witnesses.

FRANK A. BALDWIN.
